UNITED STATES PATENT OFFICE

2,215,980

METHOD OF BURNING OFF GLASSWARE

Carl W. Schreiber, Toledo, Ohio, assignor to
Libbey Glass Company, a corporation of Ohio

Application April 7, 1939, Serial No. 266,578

2 Claims. (Cl. 49—77)

The present invention relates to a method of and an apparatus for burning off glassware and more particularly to the type of apparatus shown and described in the patent to Parker No. 1,577,-538, dated March 23, 1926, wherein the article is held substantially stationary while the burner is moved relative thereto during the burning-off process.

The invention is designed as an improvement over the apparatus disclosed in the Parker patent in that means is provided for stretching the wall of the article in the region of the severing flame to avoid the formation of a bead on the rim of the article after the moil is severed from the article. 15 This being the principal object of the invention, other objects thereof will become apparent as the following description ensues.

In the accompanying drawings:

Fig. 1 is a vertical sectional view taken longitudinally and centrally on a vertical plane through an apparatus embodying the principles of the present invention;

Fig. 2 is a sectional view, diagrammatic in its representation, of a valve structure and an associated burner structure with the former in position for applying cooling air to the stretched wall of a tumbler;

Fig. 3 is a diagrammatic view similar to Fig. 2 with the valve structure in the position it occupies during the actual burn-off operation;

Fig. 4 is a diagrammatic view similar to Fig. 2 with the valve structure in position for flame treating the finished edge resulting from the burn-off operation;

Fig. 5 is another similar diagrammatic view illustrating the tumbler and moil discharge;

Fig. 6 is an enlarged sectional view taken centrally and vertically through the valve structure;

Fig. 7 is an enlarged sectional view taken centrally and vertically through the burner structure;

Fig. 8 is a fragmentary sectional view taken through a tumbler wall illustrating the relative regions at which the tumbler wall is stretched and at which the tumbler is severed from the moil; and

Fig. 9 is a fragmentary sectional view similar to Fig. 8 illustrating the manner in which the stretched wall is burned through.

Referring now to Fig. 1, the apparatus involves in its general organization a table 20 on which there is mounted at the forward side thereto a burner 21. An article support 22 is supported beneath the burner 21 by means of sleeves 23 which enclose columns 24 depending

from the table 20. The lower ends of the columns 24 are united by a cross-piece 25.

A bracket 26 depends from the rear side of the table 20 and provides a bushing for a shaft 27. The shaft 27 constitutes the main driving shaft 5 for the machine and has mounted thereon a cam wheel 28 having a cam groove 29 therein. The bracket 26 is provided with a depending extension 30 carrying a rock-shaft 32 at the lower end thereof and upon which there is fulcrumed 10 a lever 31. A roller 33 is mounted on the rear end of the lever 31 and operates in the cam groove 29. The front end of the lever 31 is connected by a link 34 to the article support 22. The link 34 is directly pivoted to a block 35 which 15 slides vertically in a guideway 36 provided in the article support 22. A pin 39 extends upwardly from the block 35 and is surrounded by a coil spring 40.

The article is directly supported upon a perforated plate 41 mounted on the support 22 and a guide ring 42 surrounds the article and is supported by arms 43 extending upwardly from the support 22. A vacuum chamber 44 is provided in the support 22 beneath the perforated plate 20 41 and is connected by a flexible hose 45 with the inlet side of a valve casing 46.

A pipe 47 leads from the casing 46 to a suitable source of vacuum such as a vacuum pump (not shown). The passage through the valve 30 casing 46 is controlled by means of a valve having a stem 48 which is normally urged upwardly to close the valve by means of spring 49 surrounding the stem. The article support 22 carries a lug 50 designed for contact with the stem 35 48 when the support is in its lowermost position as will be described hereinafter.

A column 51 extends upwardly from the table 20 and is provided with a cross-piece 52 at the upper end thereof. Pulleys 53 are rotatably mounted on the cross-piece 52 and a cable 53 passes thereover. A weight 54 is attached to one end of the cable 53 and the other end of the latter is connected to a rod 55 which is suspended from the cable. A moil clutch 56 is secured to 45 the lower end of the rod 55. The moil clutch 56 is substantially identical with that shown in the above mentioned patent to Parker and reference to this patent may be had for a full description of the character and operation thereof. The rod 50 55 extends through a stationary guide 56' which also serves to limit the upward movement of the moil clutch 56.

A combined air supply and flame control valve 57 is carried by a bracket 58 mounted on 55

the column 51 and includes a central valve core 59 (see also Figs. 2 to 5 inclusive) and a surrounding valve sleeve 60. The core 59 is slidably disposed in the sleeve 60 and is vertically slideable 5 on the rod 55 while the sleeve 60 is vertically slideable in the bracket 58. The upper end of the sleeve 60 is closed and a spring 61 surrounds the rod 55 and normally urges the core 59 downwardly and the sleeve 60 upwardly, or in other 10 words, in opposite directions relative to each other. The lower end of the core 59 projects through the sleeve 60 and is supported upon a collar 62 mounted on the rod 55.

Movement of the sleeve 60 in the bracket 58 15 is controlled by means of a cam 63 which engages a roller 64 rotatably supported at the upper ends of a pair of standards 65 (see also Fig. 6) mounted on the upper end of the sleeve 60. The cam 63 is mounted for rotation at the outer end 20 of a bracket 66 carried on the column 51 and is driven continuously through a train of driving mechanism including bevel gears 67 and 68, a shaft 69, and bevel gears 70 and 71, the latter gear being mounted on the driving shaft 27. 25 Referring now to Figs. 1 and 7, the burner 21 includes upper and lower stationary carriers 72 and 73, the latter being integrally formed with the table 20 and the former being secured to the latter. Bolted together as at 74 and thus being 30 secured together for rotation as a unit is an upper air ring 75, a spacing ring 76, an inner oxygen-fuel gas ring 77, and a lower supporting ring 78, the latter having teeth 79 formed on the periphery thereof. The burner unit 75, 76, 77, 35 78 is driven from the shaft 27 through a train of driving mechanism including bevel gears 80 and 81, vertical shaft 82, chain and sprocket mechanism 83, vertical shaft 84 and gear 85, the latter meshing with the teeth 79 on the supporting 40 ring 78.

An air conduit 86 leading from the valve 57 extends into the upper carrier 72 and communicates through a passage 87 with an annular space 88 or groove formed in the lower side of the air ring 75. A series of radial passages 89 connect the space 88 with an annular air chamber 90 the inner wall of which is provided with a series of apertures or air jets 92 by means of which cold 45 air is adapted to be directed against the stretched wall of the tumbler as will be apparent presently.

An oxygen conduit 93 and a fuel gas conduit 94 extend into a union 95 which in turn extends into the carrier 73 and communicates through a 50 passage 96 with an annular space 97 or groove formed in the underneath side of the lower supporting ring 78. A series of passages 98 connect the space 97 with an annular mixing chamber 99 provided in the oxygen-fuel gas ring 77. 55 The inner wall of the chamber 99 is perforated to provide a series of jets 100 by means of which flame is directed inwardly against the tumbler wall to sever the tumbler from the moil as will presently appear.

60 Referring now to Figs. 1 and 6, the valve core 59 is formed with an annular groove 101 designed for communication with a pair of ports 102 and 103 formed in the valve sleeve 60 when the core 59 is retracted in the sleeve 60 with the coil 61 compressed as shown in Fig. 2. The port 102 communicates with a conduit 104 leading from a source of compressed air while the port 103 communicates with the air conduit 93 leading to the burner 21.

75 The groove 101 in the core 59 is also designed

for communication with a pair of ports 105 and 106 formed in the sleeve 60 when the core 59 is in its extended position with the spring 61 extended as shown in Figs. 3 and 4. The port 105 communicates with a conduit 107 leading 5 from a source of oxygen supply while the port 106 communicates with the oxygen conduit 93 leading to the burner.

A moll pan 108 is provided for receiving the burned off moll as shown in Fig. 5 and is capable 10 of being swung to the position indicated in Fig. 1 to discharge the moll therefrom in the manner set forth in the Parker patent previously mentioned.

The operation of the apparatus is as follows: 15

With the parts in the position shown in Fig. 1, an article resting on the article support 41 is positioned within the burner 21 with the moll clutch engaging the moll portion thereof. Vacuum is applied to the chamber 44 through 20 the conduit 45 to hold the article on the support 41. The roller 64 which, together with the cam 63, controls the movements of the valve sleeve 60 is in engagement with a high portion of the cam and thus the sleeve 60 is depressed. The 25 wall of the article being comparatively cool and rigid is not yet susceptible to stretching and consequently the valve core 59 is in its lowermost position and is extended with respect to the relative positioning of the sleeve. The annular groove 101 is therefore in communication with the ports 105 and 106 and oxygen is conducted from the conduit 107 through the valve 57 and conduit 93 to the burner to be mixed with fuel 30 gas issuing from the conduit 94 and supplied 35 to the jets 100.

During movement of the cam 63 from the angular position shown in Fig. 1 to the angular position shown in Fig. 2, the roller travels on a relatively high circular portion of the former and 40 during this time the burner 21 continues to direct the jets 100 of flame against a localized area of the article wall as shown at a in Fig. 8. As soon as this localized area becomes softened under the influence of heat, the weight 54, acting through 45 the cable 53, rod 55 and moll clutch 56, causes the article wall to be stretched, thus drawing glass upwardly from the region of localized heating as shown in Fig. 8. The extent of such drawing and stretching operation is determined by the travel 50 of the valve core 59 in the sleeve 60 and at such time as the core is fully retracted therein as shown in Fig. 2, such stretching will terminate.

As shown in Fig. 2, movement of the core 59 upwardly in the sleeve 60 causes the groove to 55 move out of register with the ports 105 and 106 and into register with the ports 102 and 103. Thus the supply of oxygen to the burner 21 is discontinued and air is admitted to the jets 92 60 thereof from the conduit 104, through the valve 57 and conduit 86. Such air serves to chill and set the stretched portion of the article wall. During the chilling operation, the discontinuance 65 of the oxygen supply to the burner 21 causes the flame to become ineffective although still present in the jets 100.

As the cam 63 continues to rotate the roller 64 encounters a relatively low region of the cam as shown in Fig. 3, and thus the valve sleeve 60 is moved upwardly relative to the core 59 so that 70 the groove 101 in the latter again registers with the ports 105 and 106. The stretched portion b of the article wall having previously been cooled and consequently set, renders the weight 54 ineffective to cause further stretching thereof and 75

consequently the valve core 59 will remain stationary instead of following the upward movement of the valve sleeve 60. As soon as the groove 101 in the core 59 again registers with the ports 105 and 106, the flame is intensified by the admission of oxygen to the burner and localized heat is applied to the region *a* of the article wall and the tumbler is severed from the moil, as shown in Fig. 4.

- 10 Immediately after severing of the article in the manner previously described, the moil clutch 56 is elevated under the influence of the weight 54 until the clutch engages the stationary guide or abutment 56'. At such time, the spring 61 15 serves to maintain the core 59 extended from the sleeve as shown in Fig. 4 in order that the supply of oxygen to the burner may be continued long enough to glaze the thin edge of the tumbler, as shown additionally in Fig. 9.
- 20 Shortly thereafter the roller 64 engages an intermediate region of the cam 63 and the sleeve is partially depressed in such a manner that the groove 101 registers with neither the ports 102, 103 nor the ports 105, 106. The supply of air 25 and also of oxygen is thus terminated as shown in Fig. 5, the article support 22 is lowered, and

the moil pan 108 is swung beneath the moil clutch 56 to receive the moil thereon.

Modifications may be resorted to within the spirit and scope of the appended claims.

I claim:

1. The method of burning off hollow glassware which consists in applying a flame to a localized circumferential region extending around the ware to soften the glass in said region while simultaneously elongating the article a predetermined 10 degree to stretch the softened glass and diminish the thickness thereof, directing a blast of cooling air against the softened glass to chill and set the same, and thereafter applying a cutting flame to the chilled glass. 15

2. The method of burning off hollow glassware which consists in applying a flame to a localized circumferential region extending around the ware to soften the glass in said region while simultaneously elongating the article a predetermined 20 degree to stretch the softened glass and diminish the thickness thereof, chilling the softened glass of diminished thickness, and thereafter applying a cutting flame to the chilled glass. 25

CARL W. SCHREIBER.
